United States Patent Office.

ALBERT L. TAYLOR, OF SPRINGFIELD, VERMONT.

Letters Patent No. 80,238, dated July 21, 1868.

IMPROVEMENT IN CUTLERY.

The Schedule referred to in these Letters Patent and making part of the same.

TO ALL WHOM IT MAY CONCERN:

Be it known that I, ALBERT L. TAYLOR, of Springfield, in the county of Windsor, and State of Vermont, have invented a new and useful Improvement in Cutlery; and I do hereby declare that the following is a full, clear, and exact description thereof, which will enable those skilled in the art to make and use the same, reference being had to the accompanying drawings, forming part of this specification.

This invention relates to a new and useful improvement in cutlery, and is more especially designed for table-cutlery, knives, forks, &c.

The object of the invention is to avoid the difficulty attending the loosening of the handles on the tangs, which is caused chiefly by the washing of the cutlery in warm water, and also to avoid the loss occasioned by the breaking and checking of the handles, a contingency of frequent occurrence when horn, bone, and ivory are used as the stock or material.

My invention consists in constructing the knife or fork and the handle all out of one and the same piece of metal, the proper thickness or proportion being given the handle, so that it may be conveniently grasped and held in the hand, by twisting or winding the tang in spiral form.

The accompanying drawing represents a side view of my invention.

A represents the blade of a table-knife, B the bolster, and C the tang. These parts are all constructed out of one and the same piece of steel.

The tang C is drawn out to a proper thickness, and of such a length as to admit of its being twisted in spiral form, the diameter of the spiral being such as to fit the hollow of the hand, and of a length corresponding to the ordinary knife-handle.

The tang is made of such a shape that when twisted, the exterior of the spiral will be slightly convex.

I deem this preferable, but do not confine myself to that precise shape.

Table-cutlery has been previously constructed with the blade and handle formed out of a single piece of metal, but has not come into general use, for two reasons:

First, if the handle be of solid metal, and of suitable dimensions to fit or fill up the hollow of the hand, there is too much weight in the handle, and it is cumbrous and inconvenient. A tubular or hollow handle cannot be made in one piece with the blade.

Second. A flat handle is not practicable. It may be made sufficiently wide, but is inconvenient to handle.

Both these forms of handles have been made, and have proved to be failures; that is to say, they did not get into general use after suitable efforts on the part of the manufacturers to introduce them.

My improvement fully obviates the difficulties above alluded to, as the handles are light, and at the same time fill up the hollow of the hand equally as well as the ordinary handles in general use.

I claim as new, and desire to secure by Letters Patent—

A spiral handle for cutlery, constructed or formed out of the same piece of metal as the blade or other portion of the implement, substantially as shown and described.

ALBERT L. TAYLOR.
